UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

METHOD OF MAKING CAR PARTS.

1,125,297.

Specification of Letters Patent.

Patented Jan. 19, 1915.

Application filed June 1, 1914. Serial No. 842,154.

To all whom it may concern:

Be it known that I, WILLIAM D. FORSYTH, a citizen of the United States, and a resident of the city of Youngstown, county of Mahoning, and State of Ohio, have invented a new and useful Improvement in Methods of Making Car Parts, of which the following is a specification.

The principal object of my invention is to provide a method of making a car part from a single piece of metal which will be easy and cheap to practice and which will produce a light and strong car part.

In the accompanying drawings, which form part of this specification, and in which like reference characters refer to like parts throughout the several views, Figure 1 is a side elevation of the blank from which a car part is made according to my invention; Fig. 2 is a side elevation of the blank shown in Fig. 1, after it has been trimmed and its middle portion has been displaced; Fig. 3 is a side elevation of the blank shown in Fig. 2 in its finished form; Fig. 4 is an end elevation of the blank shown in Fig. 1; Fig. 5 is a top plan view of the blank in its finished form as shown in Fig. 3; Fig. 6 is an end elevation of the blank in its finished form; Fig. 7 is a section on the line 7—7 on Fig. 3; Fig. 8 is a top plan view of a modified form of blank. Fig. 9 is a side elevation of the modified form of blank shown in Fig. 8. Fig. 10 is a section on the line 10—10 on Fig. 8. Fig. 11 is a cross-section of another modified form of blank; and Fig. 12 is a cross-section of another modified form of blank.

The car part which is shown in the accompanying drawings is made from a structural shape 1, which has a web 2, parallel flanges 3, and fins 4. The fins 4 project from the web 2 in a direction opposite to the direction in which the flanges 3 project. The outer faces of the fins 4 are substantially in the same plane with the inner faces of the flanges 3. In order that the finished side frame may have the proper proportions, the edge portions of each flange 3 are sheared off at the ends and middle, and each flange 3 has its full width near each end and is comparatively narrow at its ends and middle, as indicated by the dot-and-dash line 5 on Fig. 1. Portions of the fins 4 are also removed from the web 2 for a short distance at each

end of said web and the corner portions of the remaining portions of said fins 4 are sheared off along lines 6 extending obliquely from the web 2 to the outer edges of said fins 4. In the web 2 are cut parallel slits 9 which extend longitudinally thereof and terminate at points 10 and 11 short of its ends. The slits 9 are so located in the web 2 as to lie between the inner faces of the flanges 3 and the outer faces of the fins 4.

After the structural shape 1 has been trimmed and slitted, its middle portion (comprising that part of said structural shape between the ends 13 and 14 of the fins 4, and including the slits 9), is displaced from its original plane so that the major part of said middle portion lies in a plane spaced from and parallel with the original plane, as shown in Fig. 2.

After the middle portion of the structural shape 1 has been displaced as described, the middle portion of the web 2, that is, the portion which is bordered by the slits 9, together with the fins 4, is displaced from its plane in a direction perpendicular to said plane; and the middle portions of the flanges 3 between the ends of said slits 9 are displaced from their plane in the opposite direction. The middle portion of the web 2 and the middle portions of the flanges 3 are displaced the same amount to form an elongated hexagonal opening 15.

The structural shape 1 after the above described operations has a shape which is adapted for use as part of a car truck side frame. The flanges 3 constitute the compression member of the side frame, and the middle portion of the web 2, together with the fins 4, constitutes the tension member. A suitable frame or bars, not shown, is fastened to the flanges 3 and the fins 4 to provide the bolster guide bars. The end portions 16 of the structural shape 1 constitute the parts to which the journal boxes are attached, and these end portions have spaced holes 17 therein through which the bolts 100 for attaching the journal boxes pass.

In the modified form of blank shown in Figs. 8 to 10, a metal plate is bent to form a channel which consists of a web 18, flanges 19, and flanges 20 on the flanges 19. In the web 18 of the channel are longitudinal slits 21 which terminate short of the ends of said web. The slits 21 have their ends closer

together than their intermediate parts. The web 18 consists of two end portions 22 and a middle portion 23 bordered by the slits 21. The edge portions of the middle portion 23 are bent down to form flanges 24. After the blank has been formed as described, it is treated in the same way as hereinbefore described.

Another modified form of structural shape, shown in Fig. 11, is an I-beam which has a web 27 and unequal flanges 25 and 26. In the web 27 are two spaced slits which extend longitudinally thereof and terminate short of its ends, as indicated by the dotted lines 28. After the web 27 has been slitted, the I-beam is treated in the way hereinbefore described.

Another modified form of structural shape, which is shown in Fig. 12, is a channel having flanges 29 and a web 30. In the web 30 are two spaced slits which extend longitudinally thereof and terminate short of its ends, as indicated by the dotted lines 31. After the channel is slitted it is treated as hereinbefore described.

The opening 15 is formed by displacing the flanges 3 and the middle portion of the web 2 the same amount and without stretching any of the metal. By displacing the middle portion of the structural shape 1 out of the plane of its end portions, that is, out of its own original plane, it is possible to bring the end portions 16 thereof nearly in line with the middle portions of the flanges 3 thereof, and likewise displace the flanges 3 and the middle portion of the web 2 the same amount. The middle portion of the structural shape 1, that is, the portion which is displaced from its original plane, is longer than the slits 9, in consequence of which the opening 15 is shorter than the distance between the inner ends of the end portions 16. For the same reason the plane of the end portions 16 is above the longitudinal median line of the opening 15, and the greatest amount of metal is at the points where the compression and tension members join.

The car part shown as made according to my invention is adapted for a car truck side frame, but other car parts may be made according to my invention.

Copies of this patent may be obtained for five cents each, by addressing the "Commissioner of Patents, Washington, D. C."

What I claim is:

1. The method of making car parts which consists in making two spaced slits in a metal blank extending longitudinally thereof and terminating short of its ends, displacing the middle portion of said blank out of the plane of the end portions of said blank, said middle portion being longer than said slits, displacing the portion of said blank included between said slits from its plane in a direction perpendicular to its plane, and displacing the side portions of said blank outside of said slits from their plane in the opposite direction to form an open frame.

2. The method of making car parts which consists in forming a blank comprising a web having flanges and fins thereon, said fins projecting from said web in a direction opposite to the direction in which said flanges project, cutting in said web two spaced slits extending longitudinally thereof and terminating short of its ends, said slits lying between said flanges and including between them said fins, displacing the middle portion of said blank so that its middle region is in a plane parallel with and spaced from its original plane, displacing the portion of said blank included between said slits from its plane in a direction perpendicular to its plane, and displacing the portions of such blank outside of said slits in the opposite direction.

3. The method of making car parts which consists in slitting longitudinally the intermediate portion of a metal blank to divide said intermediate portion into a plurality of strips integral at their ends, displacing the middle portion of said blank from its plane to lie in a plane parallel to and spaced from its original plane, displacing one of said strips of said intermediate portion from its plane in a direction perpendicular to its plane, and displacing the other strips in the opposite direction, to form an open frame.

Signed at St. Louis, Missouri, this 28th day of May, 1914.

WILLIAM D. FORSYTH.
